CHARCOAL FIRE STARTER AND GRILL

Duane L. Storandt, 12 Hanley Downs,
St. Louis, Mo. 63117

Filed Aug. 28, 1972, Ser. No. 284,239

Term of patent 14 years

Int. Cl. D7—02; D26—99
U.S. Cl. D7—107

FIG. 1

FIG. 2

FIG. 3

FIG. 5

FIG. 4

FIG. 1 is a side elevational view of a charcoal fire starter and grill showing my new design.

FIG. 2 is a front view thereof.

FIG. 3 is a bottom view thereof.

FIG. 4 is a top view thereof.

FIG. 5 is a rear view thereof.

I claim:

The ornamental design for a charcoal fire starter and grill, as shown.
